PINCH TYPE BENDING ROLL METHOD
AND MEANSJess C. Rose and George E. Stankey, Los Angeles,
Calif., assignors to Bardwell & McAlister, Los
Angeles, Calif., a corporation of California

Application July 25, 1942, Serial No. 452,306

10 Claims. (Cl. 153—56)

This invention relates generally to the art of bending linearly extended stock of various cross-sectional shapes to predetermined curvatures by means of pinch-type bending rolls, and the general object of the invention is the provision of improved methods and means for supporting the stock as it is run through the bending roll.

In bending stock by means of pinch type bending rolls, the stock is passed between two rolls which closely support or "pinch" the metal between them as it is bent. A "leading" roll supports the stock just ahead of the two pinch rolls, and a "forming" roll engages and deflects it just beyond them, causing the metal to bend at the pinch rolls. The aim in operating such bending rolls is to confine the metal closely at the pinch rolls, i. e., at the point of bend, so as to control the flow of the metal (which must be stretched at one edge and packed or shrunk at the other) in such a way as to avoid wrinkling, buckling, twisting or other distortions. Pinch type bending rolls have been very successfully used in the past to bend certain angle and other sections when the metal is of some substantial thickness. However, with relatively thin stock, say of $\frac{1}{32}$ " thickness or less, great difficulty is encountered. As a matter of fact, it has heretofore been absolutely impossible to bend light guage angle and other sections, made up for instance of stainless steel, without wrinkling or buckling the metal.

The primary object of the present invention is therefore the provision of a method and means for bending relatively light guage stock of various cross-sectional shapes by means of conventional pinch type bending rolls.

In accordance with the invention, the relatively light guage stock to be run through the bending roll is packed between and supported by means of a number of flexible supported elements, which closely confine the stock, and are passed through the bending roll along with it. These flexible elements furnish complete support for the stock as it is bent, and assure obtainment of the desired bend without otherwise deforming the metal.

The invention will be best understood by now referring to the following detailed description of certain present preferred procedures and instrumentalities in accordance therewith, reference for this purpose being had to the accompanying drawings, in which:

Fig. 1 is a plan view, with parts broken away, of a pair of spring pads with a Z-section strip packed therebetween;

Fig. 2 is a side elevation of the subject matter shown in Fig. 1;

Fig. 3 is a transverse section taken on line 3—3 of Fig. 2;

Fig. 4 is a transverse section taken on line 4—4 of Fig. 2;

Fig. 4a is a view similar to Fig. 4, but showing a modification;

Fig. 5 is a transverse section taken on line 5—5 of Fig. 2;

Fig. 6 is a schematic side elevation of a pinch-type bending roll adapted to carry out the present invention;

Fig. 7 is a section on line 7—7 of Fig. 6;

Fig. 8 is a section on line 8—8 of Fig. 6;

Fig. 9 is a section on line 9—9 of Fig. 6;

Fig. 10 is a view similar to a portion of Fig. 1, but showing a modification;

Fig. 11 is a transverse section on line 11—11 of Fig. 10;

Fig. 12 is a view similar to Fig. 6, but showing additionally the use of a side thrust roller designed to impart a curvature to the stock in a direction at right angles to the direction of bend normally imparted by the bending roll; and

Fig. 13 is a view taken as indicated by line 13—13 in Fig. 12.

Figs. 6 to 9, inclusive, show schematically a fore or less conventional pinch-type bending roll, such as may be utilized in practicing the present invention; for a more complete disclosure of such

30 a bending roll, see our Patent No. 2,335,028 entitled "Pinch type bending roll" issued November 23, 1943. This bending roll comprises two pinch roll shafts 20 and 21, either one of which, or both, may be driven through any suitable driving ar-

35 rangements. Shaft 20 carries a series of three rolls 22, 23, and 24, of which rolls 22 and 24 are of the same diameter, and roll 23 is of a lesser diameter, as typically shown in Fig. 7. Shaft 21 carries a single roll 25, a marginal portion of

40 which is received in the space between the rolls 22 and 24.

The peripheries of the opposed rolls 23 and 25 together with portions of the side faces of rolls 22 and 24 define a rectangular opening or passageway for the stock to be bent and the flexible supporting elements, as presently to be described.

Ahead of the pinch roll shaft is a leading roll 26, which idles on a suitable spindle 27, and which comprises three disks 26a, 26b and 26c defining a groove 28 adapted to receive and confine laterally the stock and supporting elements therefor. Beyond the pinch-roll shafts 20 and 21 is the usual forming or bending roll 30, also in this instance comprising three disks 30a, 30b and 30c defining a groove 31 adapted to receive and con-

fine laterally the stock and supporting elements therefor, this roll 39 being mounted on a shaft 32, which may be driven, through any suitable arrangements not necessary here to illustrate, so as to impart to disk 30b defining the bottom of groove 31 rotation at the same peripheral speed as pinch roll 25, the rolls 30 and 25 of course turning in the same direction.

Assuming the member S to be formed to be, for instance, of Z-section (see Fig. 4), the procedure is as follows: The member S is packed between two sets or pads 40 of long, flat spring elements or leaves 41, the web 42 of the Z-section member being abutted by the longitudinal edges of the spring leaves of each pad, and each pad being of a thickness substantially equal to the height of the web of the Z-section member plus the thickness of one of its flanges. These leaves 41 are preferably slightly greater in width than the widths of the flanges 43 of the Z-section member, and they are preferably formed of spring steel, of a thickness of the order, typically, of .031", though this is subject to modification. In Figs. 1 and 2, a substantial portion of the lengths of the spring pads and Z-section member have been broken out. It is to be understood that these members may be of any length; for instance, for a Z-section member of a length of 6', the spring pads may be 7' in length. They should in any case be at least approximately one foot longer than the stock to be bent.

Leaves 41 of each spring pad 40 are preferably integrated at the nose ends of the pads; for instance, as indicated at 44 in Fig. 2, the leaves may be brazed each to the next for a distance of an inch or an inch and a half at the nose ends of the pads. The brazing material is not only applied along the edges of the spring leaves, but sweated in between them so that, in effect, the spring pad is made solid at its nose end.

The two pads 40, with the Z-section member S packed therebetween, are preferably provided with an encircling band 46, which secures the pack in assembly and which is slidably mounted on the pads, so that it can be manually moved in a rearward direction, and finally pulled off the rearward ends of the pads as the pads go into the bending roll.

The longitudinal edges of spring pads 40 support the web 42 of member S during the bending operation, but leave the flanges 43 unprotected and subject to wrinkling. To support these flanges 43, long, flat spring members or leaves 47, formed of spring steel, and of widths approximately double the widths of the spring leaves 41, are placed at the top and bottom sides of the pack, in such manner that one-half of each such member 47 lies flat against the otherwise exposed face of one of the flanges 43. The other halves of the members 47 engage the opposed spring pad 40, as clearly shown in Fig. 4. These members 47 are made as thick as possible consistent with bending through the curved path which they must follow, and may be of thicknesses ranging typically between $\frac{1}{8}$ " and $\frac{1}{4}$ ", though this is of course not to be taken as limitative.

The pack P as thus assembled is then run through the bending roll as a unit, the encircling band 46 being moved in a rearward direction on the pads as the pack goes into the bending roll, being finally removed from the rearward ends of the pads.

The pads 40 will be understood to be of such widths that, taken together with the thickness of the web 42 of the member S to be bent, the total

thickness dimension of the pack is such as will just be received, with comparatively close-sliding fit, between the rolls 22 and 24 of the bending roll (see Fig. 7), and adjustments are so made that the vertical thickness of the pack, measured between the outside faces of the two outside spring leaves 47, is such as will just permit the pack to be received between the rolls 23 and 25, the latter "pinching" the pack between them with a pressure such as is usual in the operation of pinch-type bending rolls. It will be understood that in conventional pinch-type bending rolls, the two shafts 20 and 21 carrying the rolls 23 and 25 are vertically adjustable relatively to one another, and this adjustment is so made as to apply the proper pressure to the pack. The longitudinal edges of the spring leaves 41 making up the two spring pads 40, as thus confined between the lateral faces of the two rolls 22 and 24, support the full width of the web 42 of the member S which is to be bent, and the two flat spring members 47, in cooperation with the pads, confine and support the flanges 43. The spring pads 40, as well as the spring members 47, conform readily to the curved path for which the bending roll is adjusted, and the member S is bent to the desired shape, and because of the support provided, assumes such shape without wrinkling, buckling, twisting or becoming otherwise deformed. The close support provided for the member S on all its surfaces thus permits it to be shrunk and stretched in different portions without introduction of the various distortions which have heretofore been inevitable with relatively light gauge material.

The invention is of course not restricted in application to the particular Z-section stock chosen for illustrative purposes. Fig. 4a, for instance, which is a view similar to Fig. 4, shows a modification of the set-up for a member S' of angle section. In this instance, the set-up is the same as before, with the exception that, the member S' having but one flange 48, but one of the flat spring members 47 is needed. Otherwise, the spring pads may be the same as before, the web 49 of the angle member S' being in this instance confined between the spring pads 40 the same as the web 42 of the Z-section member S described first.

Figs. 10, 11, 12 and 13 show a modification of the invention which is employed when the stock is to be bent in two directions, one at right angles to the other. In such a case, the bending roll is equipped with an additional roll 50, which is of a width substantially equal to the thickness of a spring pad, and which engages the lateral edge of the adjacent spring pad just beyond forming roll 30. In this instance, each pad, here designated by numeral 40a, and which, excepting for departures noted, will be understood to be the same as the pad 40, is so formed as to be flexible in two directions. To accomplish this, the pad may be made up of a plurality of rods or bars 41a, flexible in both directions, and preferably of square or rectangular cross-section, as illustrated in Fig. 11. The stock S has again been illustrated as a member of Z-section, though this is of course not limitative, and the stock might equally as well be of angle or other section. The stock S being of Z-section, however, the two flanges 43 thereof are again supported by long, flat spring members or leaves 47, like the spring members 47 of Figs. 2 to 5. It will be understood that the lateral thrust roller 50 of the bending roll will engage the adjacent pad 40a between the

members 47, which are not laterally flexible, and function to deflect the pads 40a and the stock in a lateral direction, so as to impart to the latter the desired lateral curvature.

The above description of typical procedures and instrumentalities for carrying the instant invention into effect will serve to impart a complete knowledge of the principles underlying the invention, and will enable the invention to be applied to stock of various cross-sectional forms not here specifically illustrated. Also, as will be evident, the particular illustrative procedures and instrumentalities are susceptible to considerable variation and modification without departing from the spirit and scope of the invention or of the appended claims.

We claim:

1. The method of bending relatively thin linearly extended sheet metal stock whose cross section includes a longitudinal web that is parallel to the plane of the bend, and a flange joined to an edge of said web and disposed at right angles thereto, by means of a pinch type bending roll, that includes packing a pair of linearly extended spring pads against opposite surfaces of said web, and with the pad on one side of the web abutting said flange, said spring pads being flexible in the direction the stock is to be bent, applying a flat spring leaf against the exposed face of said flange, so as to pack said flange between the one spring pad and said spring leaf, and passing the stock together with said pair of spring pads and leaf spring through the bending roll.

2. The method of bending relatively thin linearly extended sheet metal stock whose cross section includes a longitudinal web that is parallel to the plane of the bend, and a flange joined to an edge of said web and disposed at right angles thereto, by means of a pinch type bending roll, that includes packing a pair of linearly extended spring pads against opposite surfaces of said web, and with the pad on one side of the web abutting said flange, said spring pads each comprising a plurality of parallel spring elements which are flexible in the direction the stock is to be bent, applying a flat spring leaf against the exposed face of said flange, so as to pack said flange between the one spring pad and said spring leaf, and passing the stock together with said pair of spring pads and leaf spring through the bending roll.

3. The method of bending relatively thin linearly extended sheet metal stock whose cross section includes a longitudinal web that is parallel to the plane of the bend, and a flange joined to an edge of said web and disposed at right angles thereto, by means of a pinch type bending roll, that includes packing a pair of linearly extended spring pads against opposite surfaces of said web, and with the pad on one side of the web abutting said flange, said spring pads each comprising a stack of parallel flat spring leaves whose longitudinal side edges engage the web, applying a flat spring leaf against the exposed face of said flange, so as to pack said flange between the one spring pad and said spring leaf, and passing the stock together with said pad or spring pads and leaf spring through the bending roll.

4. The method of bending relatively thin linearly extended sheet metal stock whose cross section includes a longitudinal web that is parallel to the plane of the bend, and flanges joined to opposite edges of said web and disposed at right angles thereto, by means of a pinch type bending roll, that includes packing a pair of lin-

early extended spring pads against opposite surfaces of said web, and with each flange supported by an abutting spring pad, said spring pads being flexible in the direction the stock is to be bent.

5. applying flat spring leaves against the exposed faces of said flanges, so as to pack each said flange between a spring pad and a spring leaf, and passing the stock together with said pair of spring pads and said spring leaves through the bending roll.

6. The method of bending relatively thin linearly extended sheet metal stock whose cross section includes a longitudinal web that is parallel to the plane of the bend, and flanges joined to opposite edges of said web and disposed at right angles thereto, by means of a pinch type bending roll, that includes packing a pair of linearly extended spring pads against opposite surfaces of said web, and with each flange supported by an abutting spring pad, said spring pads each comprising a plurality of parallel spring elements which are flexible in the direction the stock is to be bent, applying flat spring leaves against the exposed faces of said flanges, so as to pack each said flange between a spring pad and a spring leaf, and passing the stock together with said pair of spring pads and said spring leaves through the bending roll.

7. The method of bending relatively thin linearly extended sheet metal stock whose cross section includes a longitudinal web that is parallel to the plane of the bend, and flanges joined to opposite edges of said web and disposed at right angles thereto, by means of a pinch type bending roll, that includes packing a pair of linearly extended spring pads against opposite surfaces of said web, and with each flange supported by an abutting spring pad, said spring pads each comprising a plurality of parallel spring elements which are flexible in the direction the stock is to be bent, applying flat spring leaves against the exposed faces of said flanges, so as to pack each said flange between a spring pad and a spring leaf, and passing the stock together with said pair of spring pads and said spring leaves through the bending roll.

8. The method of bending a relatively thin linearly extended member of uniform cross-section in a pinch type bending roll, said member having surfaces likely to become deformed during the bending operation, that includes setting up the pinch rolls of the bending roll to define a passageway for the member of rectangular cross-section and of greater cross-sectional area than the member, packing the member between a plurality of flexible longitudinally extending elements closely engaging and supporting said surfaces, forming said elements and member into a pack of cross-sectional size conforming to said

passageway defined by said pinch rolls, and passing the pack longitudinally through said passageway.

9. A spring pad flexible in two directions at right angles to one another comprising a bundle of parallel linearly extended spring elements flexible in two directions arranged in a plurality of contacting vertical and horizontal rows and integrated to one another at one end.

10. Means for packing a relatively thin linearly extended sheet metal member whose cross section includes a longitudinal web parallel to the plane of the bend, and a flange joined to an edge of

said web and disposed at right angles thereto, during bending thereof in a pinch type bending roll, comprising: a pair of linearly extended spring pads consisting of a stack of relatively thin spring leaves adapted to be positioned adjacent opposite surfaces of said web, and with the pad on one side of the web in engagement with the inside surface of said flange, and a spring leaf relatively thicker than the aforementioned spring leaves adapted to be applied to the outside surface of said flange.
